UNITED STATES PATENT OFFICE

GEORGE W. COPE, OF DETROIT, MICHIGAN, ASSIGNOR TO C. EMRICH, OF COLUMBUS, OHIO.

DESIGN FOR A STOVE OR RANGE.

SPECIFICATION forming part of Design No. 27,723, dated October 12, 1897.

Application filed August 11, 1897. Serial No. 647,928. Term of patent 7 years.

To all whom it may concern:

Be it known that I, GEORGE W. COPE, a citizen of the United States, residing at Detroit, in the county of Wayne and State of Michigan, have invented and produced a new and useful Design for Stoves or Ranges, of which the following is a specification, reference being had therein to the accompanying drawings.

1. The leading feature of my design consists in the configuration and ornamentation as hereinafter described, and shown in the drawing, which represents a perspective view of my design for a stove.

2. The leading feature of the ornamentation are the numerous irregular-sized and irregularly-distributed panels formed by the scroll-work which serves as the border or frame of the panel, the panel being made convex or 5 protuberant, whereby in connection with the heavy scroll the ordinary flat look of surface decoration is effectively destroyed, and the character of relief-work is imparted to the design similar to that produced by stamping sheet metal between dies.

3. The legs A of the base are ornamented by a scroll B, which forms two protuberant bosses C and D, and the skirting between the legs has two protuberant panels E E, with a rosette-like ornament F between them, and ornamental scrolls G G adjacent to the legs.

4. The oven-door H has an oblong-curved panel I upon it. Each panel is made to protrude considerably, and above and below it are the scroll-panels J and K, which panels conform to the shape of the panel I.

5. Another scroll-panel L is formed upon that portion of the door to which the handle M is secured. Below the door is an ornamental shelf N, formed with open scrollwork.

6. The reservoir O has two smooth panels P and Q of the general character described.

R and S are scroll-panels upon the oven-doors, respectively, and T is an ornamental panel between the stove-doors.

45

The hearth U is provided with an extension V, upon which is formed a standing flange W. Below the hearth U is a shelf X, formed with open scrollwork.

7. The warming-shelf a is decorated with a scroll upon its edge and is supported by an ornamental standard resting upon an ornamental base b, which supports the warming-shelf c c and has a number of scroll-panels d e f, of the character described, upon the 55 wings.

8. The standard is bordered upon its sides by the heavy scrolls e' in the form of supports for the shelf, and upon the central portion or smoke-flue is the scroll-panel f' and upon the 60 wing portions are scroll-panels g. Above the latter the standard is decorated with network h, which in appearance is fastened to the scrolls e', and above the net on each wing is the scroll-evolute i.

65

9. What I claim as my invention is—

1. The design for a stove or range substantially as shown and described.

2. In a stove or range, the design for the leg and skirting, substantially as shown and 70 described.

3. In a stove or range the design for the oven-door, substantially as shown and described.

4. In a stove or range, the design for a 75 standard supporting the warming-shelf, substantially as described.

In testimony whereof I affix my signature in presence of two witnesses.

GEORGE W. COPE.
